United States Patent Office

Des. 197,156
Patented Dec. 17, 1963

197,156

AIRCRAFT FUSELAGE

Thomas A. Hartman, 700 Capac Court, St. Louis, Mo.

Filed May 7, 1963, Ser. No. 74,780

Term of patent 14 years

(Cl. D71—1)

Fig. 1

Fig. 2

Fig. 3

FIG. 1 is a perspective view of an aircraft fuselage, showing my new design;

FIG. 2 is a front elevational view;

FIG. 3 is a rear elevational view;

FIG. 4 is a side elevational view;

FIG. 5 is a top plan view; and

FIG. 6 is a bottom plan view.

I claim:

The ornamental design for an aircraft fuselage, as shown.
